(57) **CLAIM**

The ornamental design for an adaptable assistance tool appliance, as shown and described.

DESCRIPTION

FIG. 1 is a front perspective view of an adaptable assistance tool appliance, showing the new design;

FIG. 2 is a front view thereof;

FIG. 3 is a back view thereof;

FIG. 4 is a side view thereof, the opposite side being a mirror image thereof;

FIG. 5 is a top view thereof;

FIG. 6 is a bottom view thereof;

FIG. 7 is an alternative embodiment thereof; and,

FIG. 8 is an exemplary diagram of the use of the an adaptable assistance tool appliance in an environment thereof the broken lines being shown for illustrative purposes only and form no part of the claimed design.

Any showing of the environment and/or drawing disclosure and/or tool by broken lines is for illustrative purposes only and forms no part of the claimed design.
